UNITED STATES PATENT OFFICE.

CHARLES D. ADAMS, OF JACKSONVILLE, FLORIDA.

STOCK-CAR DOOR AND GANGWAY.

1,276,305.

Specification of Letters Patent. Patented Aug. 20, 1918.

Application filed February 23, 1918. Serial No. 218,794.

To all whom it may concern:

Be it known that I, CHARLES D. ADAMS, a citizen of the United States, residing at Jacksonville, in the county of Duval and State of Florida, have invented certain new and useful Improvements in Stock-Car Doors and Gangways, of which the following is a specification, reference being had therein to the accompanying drawing.

10 The invention relates to stock car doors and gangways and has for its object to provide a door, that will prevent the stock from turning from the gangway, as they are being unloaded on to platforms. It has been found that stock, when being unloaded on to a platform, from a stock car, over the usual gangway, will at times fall from the same, between the car and the platform if they should turn to the right or the left 20 while leaving the car over the ordinary gangway now in use.

A further object is to so construct the car door so that a portion of the door will form a gangway, while other portions of the door will form side guards for the gangway when the car is being unloaded. Also to provide a combination stock car door and gangway provided with guards.

25 A further object is to so construct the door, so that the gangway section will hinge downwardly, on to the unloading platform, and the guard sections will slidably move downwardly, upon guide posts and hinge outwardly forming side guards for the 35 gangway and be held against movement by means carried by the sides of the gangway.

A further object is to provide locking means, whereby the sections of the door, will be locked, in relation to each other when 40 the car door is closed.

With the above and other objects in view, which will appear as the description proceeds, the invention resides in the details of construction and combination of parts 45 hereinafter described and claimed, it being understood that changes in the precise embodiment of the invention herein described may be made within the scope of what is claimed without departing from the spirit 50 of the invention.

Figure 1 is a view of a portion of a stock car, showing the door applied thereto.

Fig. 2 is a sectional view on line 2—2 of Fig. 1.

55 Fig. 3 is a sectional view on line 3—3 of Fig. 1.

Fig. 4 is a sectional view through a portion of a stock car and the door thereof, showing the door open and the gangway in position for unloading stock. 60

Fig. 5 is a perspective view of one corner of the gangway, showing one of the doors in position for engaging the end of the gangway.

Referring to the drawings, 1 designates a stock car and 2 one of its side walls. The wall 2 is provided with the usual door opening 3. Secured adjacent the sides of the door opening 3, by means of the rivets 4 are posts 5, which are parallel with the sides 70 of the door opening. Pivotal and slidably mounted upon the posts 5, by means of hinges 6 are doors 7, which are shorter than the height of the door opening and are designed to form sides for the gangway, 75 when the door is open and the gangway in position for unloading stock. The lower or gangway section 8 of the car door pivots upon the rod 9, which is mounted in the bearings 10 carried by the side sill 11 of the 80 car, said door being pivotally connected to the rod 9 by means of the hinges 12, which in turn are riveted or otherwise secured to the gangway section 8 of the door. The gangway section 8 of the door is provided 85 with a keeper plate 14, having enlargements 15, adapted to be engaged by the sliding bolts 16 of the barrel bolts 17, which are riveted to the corners 18 of the doors 7 thereby locking the doors and the gangway 90 securely together, when the door, as a whole is closed. Secured to the corners 19 of the doors 7, by means of rivets 20 are pins 21, which are adapted to engage the sockets 22 of the retaining plate 23 secured to the 95 longitudinal top beam 24 by means of rivets 25.

Secured to the corners 26 of the gangway section 8 of the door, by means of rivets 27 are angle bars 28. These angle bars 28 are 100 provided with arms 29 and are adapted to engage the vertical posts 5 when the car door is closed. When the gangway is in position for unloading, the arms 29 form means for retaining and preventing movement of the door sections which when in unloading position form side guards for the gangway.

To open the door and form a gangway for the stock to pass over to the unloading 110 platform 30, the sliding bolts 16 are moved upwardly, after which the gangway section

8 is swung downwardly until its free end rests upon the unloading platform 30. Then the door sections are allowed to slide downwardly until the pins 21 are out of engagement with the sockets 22 and when out of engagement, the door sections 7 are swung outwardly until they are at right angles to the side of the car, when in this position they are allowed to slide downwardly upon 10 the posts 5 until their lower ends rest upon the angles 28, between the edges 32 of the gangway section 7 and the arms 29 of the angles, thereby preventing swinging of the doors or guards 7 when in unloading positions.

It will be seen that a combination stock car door and unloading gangway and guards therefor is provided in which it will be impossible for the stock to turn from or fall 20 off during the unloading of the car. It is also obvious that the sections of the door are positively locked together when the car door is closed.

The invention having been set forth, what 25 is claimed as new and useful is:—

1. A stock car door comprising a horizontally pivoted gangway section, vertical posts secured in a door opening, pivoted guard sections slidably mounted on said posts, retaining brackets carried by the sides of the 30 gangway section for the reception of the lower ends of the guard sections when the gangway is in position for unloading, said retaining brackets being so positioned that they will engage the posts in the door opening and limit the inward movement of the gangway section when the same is closed and means for locking the guard and gangway sections in relation to each other when 35 the door is closed.

2. A stock car door comprising a horizontally pivoted gangway section having retaining brackets at its sides, vertical posts

secured in a door opening, vertically pivoted 45 guard sections carried by said posts and so constructed that when the gangway section is in a position for unloading the lower ends of said guard sections will engage the retaining brackets carried by the sides of the gangway section, said retaining brackets being 50 so positioned that they will engage the posts and be limited in their inward movement when the gangway is closed and means whereby the gangway and guard sections may be locked when the door is closed. 55

3. A stock car door comprising a horizontally pivoted gangway section having retaining brackets at its sides, vertically pivoted 60 guard sections so constructed that when the gangway section is in a position for unloading said guard sections will engage said retaining brackets and form side guards for said gangway.

4. A stock car door comprising a horizontally pivoted gangway section, vertically 65 pivoted and slidably mounted guard sections and means carried by the gangway section for the reception of the lower ends of the vertically pivoted and slidably mounted guard sections when the gangway is in 70 position for unloading.

5. A stock car door comprising a horizontally pivoted gangway section, vertically pivoted and slidably mounted guard sections, said guard sections having means for 75 engaging sockets in the door frame when in extreme vertical positions, said gangway section maintaining the guard sections in extreme vertical positions when the door as a whole is closed and means for locking the 80 guard sections and gangway section in relation to each other when in closed position.

In testimony whereof I hereunto affix my signature.

CHARLES D. ADAMS.
